United States Patent Office.

GILES F. FILLEY, OF ST. LOUIS, MISSOURI.

Letters Patent No. 80,935, dated August 11, 1868.

IMPROVEMENT IN COAL-STOVES.

The Schedule referred to in these Letters Patent and making part of the same.

TO ALL WHOM IT MAY CONCERN:

Be it known that I, GILES F. FILLEY, of the city and county of St. Louis, and State of Missouri, have invented a new and useful Improvement in Coal-Stoves, of which the following is a full, clear, and exact description, reference being had to the annexed drawing, representing a vertical section of my invention, and making a part of this specification.

The object of my invention is to produce a stove specially adapted to the burning of bituminous coal, and so constructed that the gases and smoke may be almost wholly consumed, thus economizing fuel and increasing the heating power of the stove.

The box A of the stove is constructed in the ordinary manner, and on this is fastened, in any suitable way, an inverted cone-shaped fire-pot, B, having an open grate, *a*, at the bottom, while its top is constructed with a flange, *b*, as shown, and a projection, *c*, forming the lower side of the opening closed by the door *h*. Inside of this flange are placed several lugs, one of which, *d*, is seen.

A second cone, D, whose base is exactly the size of that of B, is then placed on top of B, its base resting on the lugs before mentioned, and inside the flange *b*, which, however, does not clasp it tightly, but leaves an open space or air-streak, *s*, between it and B, as seen. A projection, *p*, from D, forms the other side of the opening closed by *h*.

The cone D has an opening, *e*, at its apex, about six inches in diameter, depending somewhat on the size of the stove, this being about the average diameter, however.

A diaphragm, H, supported by the studs *m* *m'*, resting on the dome D, and by the casing, N, around the fire-pot, has above it a hot-air chamber, O, having either at its top or side an exit-pipe for the products of combustion.

The casing N is made of open work, as shown, and, while it gives a more finished appearance to the stove, is not essential to its perfect operation, and, being open, does not interfere with the draught.

Through these openings in the casing the cold air passes into and through the space between the fire-pot and dome, as shown by the dark arrows, and mingles with the gases at the best point to produce the most perfect combustion, since its point of union is nearly at the surface of the burning coal, and before the temperature of the carbon of the gas is reduced below that of ignition, which has been proved to be an all-important condition to the attainment of the result here sought.

To still further increase the volume of cold air introduced, the door may be perforated, as has been frequently done heretofore for this purpose.

The usual draught through the coal is obtained through the openings in the box A, as shown.

The currents of heated air are indicated by the red arrows, while the dark ones show the cold-air currents.

I am well aware that cold air has heretofore been introduced above the fire-pot to improve combustion, and consequently I do not claim any novelty in such a device, nor in the shape of the fire-pot; but

What I do claim as my invention, and desire to secure by Letters Patent, is—

Forming the fire-pot of a coal-stove of two cones, B and D, having an opening or air-streak, *s*, between their bases, for the admission of atmospheric air, when the same are arranged, constructed, and operate substantially as herein set forth.

GILES F. FILLEY.
